(57) **CLAIM**

The ornamental design for a unit for light control, as shown and described.

DESCRIPTION

FIG. 1 is a perspective view from the front, bottom, and right side of a unit for light control showing our new design; FIG. 2 is a front view of the unit for light control of FIG. 1; FIG. 3 is a rear view of the unit for light control of FIG. 1; FIG. 4 is a top view of the unit for light control of FIG. 1; FIG. 5 is a bottom view of the unit for light control of FIG. 1;

FIG. 6 is a left side view of the unit for light control of FIG. 1; and,

FIG. 7 is a right side view of the unit for light control of FIG. 1.

The broken lines are included for the purpose of illustrating portions of the unit for light control and form no part of the claimed design.

1 Claim, 4 Drawing Sheets
